UNITED STATES PATENT OFFICE.

DE KERNIA J. T. HIETT, OF CHICAGO, ILLINOIS, ASSIGNOR TO JOHN H. COULTER, OF CHICAGO, ILLINOIS.

VENTILATOR.

1,073,125.

Specification of Letters Patent. Patented Sept. 16, 1913.

Application filed July 14, 1911. Serial No. 638,455.

To all whom it may concern:

Be it known that I, DE KERNIA J. T. HIETT, a citizen of the United States, residing at Chicago, in the county of Cook and 5 State of Illinois, have invented certain new and useful Improvements in Ventilators, of which the following is a specification.

This invention relates to improvements in ventilators, and refers more specifically to 10 an improved ventilator of that type in which the ventilation is induced by drafts of air sweeping across the eductive part of the ventilator, as distinguished from those ventilators which employ movable parts for 15 propelling the air.

Among the salient objects of the invention are to provide a construction which is available for ventilating both movable and stationary compartments, as for example 20 cars and dwelling houses; to provide a construction which is effective in any position of adjustment, *i. e.*, upstanding, horizontally disposed or inverted; to provide a construction which is self-cleaning, *i. e.*, which operates in such manner as to avoid indrafts and 25 practically render impossible the entering of dust, dirt or rain; to provide a construction which is about equally effective regardless of which direction the eduction draft 30 sweeps across the ventilator, thus making the ventilator admirably suited for out of door use where the drafts of outer air are depended upon to produce the eductive ventilation; to provide a construction which 35 may be made extremely compact and therefore fitted into small spaces or adjusted in position where limited clearance is provided; to provide a construction which may be very economically manufactured from 40 any suitable material; to provide a construction which may be made round, square, or of other preferred cross sectional contour and nevertheless remain fully effective; to provide a construction which dispenses with 45 all moving parts and is therefore free from danger of becoming inoperative; to provide a construction in which the discharge end of the ventilator is (preferably) covered over by a member which serves the double 50 purpose of enhancing the operative efficiency of the ventilator and at the same time protects the latter against injury and entrance of larger missiles; and in general, to provide an improved construction of the character referred to.

To the above ends the invention consists in the matters hereinafter described, and more particularly pointed out in the appended claims.

The invention will be more readily understood from a description thereof in connection with the illustrative drawings showing preferred embodiments.

In the drawings—Figure 1 is a cross sectional fragmentary view of the upper parts 60 of an ordinary car, the opposite sides of which are provided with ventilators of two different types, each embodying my invention; Fig. 2 is a view partially in perspective and partially in section showing details 65 of the ventilator shown at the right hand side of Fig. 1; Fig. 3 is an axial sectional view of the ventilator shown in Fig. 2; Figs. 4 and 5 are views similar in character to Figs. 2 and 3 but showing details of the 70 ventilator shown at the left hand side of Fig. 1.

Referring to the drawing, and describing first the embodiment of the invention shown at the right of Fig. 1 and in Figs. 2 and 3, 1 80 designates as a whole an outer shell or casing, which in this embodiment comprises a cylindrical trunk portion 2 and an outwardly flaring extension portion 3. The trunk communicates with the compartment to be ventilated and the extension is freely exposed to outside currents of air. Leading into the sides of the extension 3 are a plurality of draft passages, designated 4, there being 85 four shown in this instance, and these arranged in quadrangular relation. Each passage has a free open intake end or mouth which is preferably approximately about as long as the axial length of the extension portion 3 will readily permit, and the width 90 of the passage may be varied at will, the intention being to provide a free inlet passage which will admit the air impinging against the side of the ventilator. The sides and the bottom of said passages are closed 95 by walls 6, 6, and 7, respectively; the bottom or radially inner wall being inclined from the inner end of the inlet opening to a point at or near the center of the outer or delivery end of the ventilator. Inasmuch as these passages 4 are arranged in 100 diametrically opposed pairs, it follows that air entering through any given one of these passages will be deflected upwardly or axially outwardly, as the case may be, depend- 105 110

ing on the position in which the ventilator is set by the inclined bottom of the receiving passage and will then find a free escape by passing out through the opposed passage, and in so doing will tend to make a more or less abrupt turn or deflection in its course. In order to insure such abrupt deflection of the air entering one passage and passing out through the opposed passage, I provide a combined baffle plate and cover 9, which is supported opposite and parallel with the delivery end of the ventilator, but spaced away from the latter by means of suitable bracket-like supports 8, 15 as indicated best in Figs. 1 and 3. This baffle plate is set close enough to the end of the ventilator shell to insure that a large proportion of the air entering through the inlets at one side of the ventilator will be deflected back and out through the opposed inlets, and this abrupt deflection of the air just opposite the central portion of the ventilator is a matter of great importance inasmuch as it is this which brings about a 20 most effective aspirating or siphoning action upon the air which is to be exhausted and as will now be explained.

The interior of the extension part of the shell is in open communication with the conduit formed by the trunk portion 2, except in so far as it is occupied by the walls of the passages hereinbefore described. That is to say, the outer end of the shell of the ventilator is open and unobstructed, except as occupied by the partitioned off conduits 4, and the space within the extension is in open communication with the interior of the trunk. The flow of the outer air through the passages 4 and between the end 30 of the ventilator shell and the baffle plate 9 produces a strong aspirating effect upon the body of air within the main part of the shell of the ventilator and induces an outflow from the compartment which is being ventilated through the ventilator. This aspirated air, of course, commingles with the currents of air which flow in through the passages 4 as well as that air which sweeps through the open space between the baffle 35 plate and the end of the shell.

It is to be observed that the outwardly expanded or enlarged form of the extension 3 compensates for the cubical space taken up by the conduits or passages 4, so that the volume of air passing outwardly through the trunk is practically unrestricted in passing through the enlarged extension, notwithstanding the latter is partly occupied by the conduits or passages. It 45 is also to be observed that the aspirating or siphoning effect is not solely due to the air which flows in through that particular intake passage 4 facing toward the source of air but those intake passages which would appear to lie in a neutral position, *i. e.*, at

right angles to the current, are also deflected for the reason that the air encountering the rounded side of the ventilator is deflected around the latter and thus more or less compressed, and upon arriving opposite the then lateral inlets close into the latter eddy-fashion, and thence out through the far side of the ventilator between the end of the latter and the baffle plate. The effect of these eddy-like inflowing currents, 70 in conjunction with the directly inflowing currents is to practically surround the intervening discharge passages at either side of the main inflow passage, *i. e.*, the one facing the wind, and it thereby produces a 75 much more pronounced aspirating effect. Moreover, the volume of air delivered against the baffle plate by these several in-taking passages produces a very strong or relatively rapid and somewhat compressed 80 outflow of air at the lee side of the ventilator which, of course, sweeps over the delivery passages which communicate with the main trunk in the lee half of the ventilator. The combined effect is to produce a very 85 strong induced outflow from the compartment through the ventilator, and this without any tendency whatever of the outer air to whiffle back into the compartment through the ventilator. 90

Another peculiarity of the construction now being described, which undoubtedly somewhat enhances its efficiency is due to its flaring exterior when mounted to extend at right angles with, and relatively close to, 100 a plain surface, as for example when mounted in the side of the upper deck of a car, as illustrated in Fig. 1. In such event the flaring part of the ventilator overhangs so-to-speak the surrounding plain surface from 105 which it extends, and the plain surface acts somewhat in the manner of a deflector to increase the flow of air into the opening or openings at the windward side of the ventilator. 110

I have further found that the aspirating effect of the ventilator is better when the baffle cover 4 is perforated more or less at points directly opposite the delivery ends of the passages 4. As best shown in Fig. 2, 115 I prefer to provide a row of perforations 14 opposite each conduit 4, and since these conduits lie at right angles to each other the perforations will likewise take the form of two rows crossing each other at right angles. 120

In the modification shown at the left hand side of Fig. 1, and in detail in Figs. 4 and 5, the same principle of operation is involved. In this instance the ventilator comprises an outer shell, designated as a whole 1', and 125 consisting of a reduced trunk portion 2' and larger extension 3'. The extension 3' is in this instance rectangular in cross section and the trunk 2' may or may not be rectangular as preferred, the one shown being circular 130

in cross section. The intake passages 4' are in general constructed like the corresponding passages 4 of the previously described ventilator, but in the modification, 5 instead of extending to and practically meeting at the center of the ventilator, these passages are so arranged as to leave a central eduction outlet 10 which communicates with the main trunk, as do also the four passages 10 11 located at the four corners of the part 3'. The end of the trunk 2' is extended a short distance inside of the side walls of the shell 3', as indicated at 12, Fig. 5, and since the trunk is cylindric and the extension 3' rec- 15 tangular, inlet passages 13 are formed at these four corners leading from the outside into the interior of the ventilator. These inlet passages 13 are thought to contribute somewhat to the uniformity and efficiency 20 of the action of the ventilator but are not regarded as essential. It is to be noted, however, that the larger cross sectional area of the part 3' on the ventilator in this modification as in the previous form compensates 25 for the space occupied by the intake passages 4'. The modification now being described is provided with a baffle cover 9', which is shown as roof-shape, *i. e.*, made outwardly convex, and because it is so made the mar- 30 ginal portions thereof may be brought somewhat closer to the end margin of the body 3', as shown clearly in Fig. 5. This venti- lator is also provided with restricted outlets or perforations 14' opposite each of the 35 several take passages 4'. The construction now being described is perhaps better adapted to use in an upright position, since rain, snow and sleet is somewhat more efficiently carried off by the convex cover and baffle 40 plate 9'. In operation this device has much the same inductive action as that previously described, although its inductive effect fluctuates more as the direction of the wind veers or as the direction of the car changes 45 with reference to the direction of the wind, if it be mounted upon a car. That is to say, owing to the rectangular form of the main body, if the latter have one of its sides squarely facing the wind, there will be less 50 eddy inflow through the lateral intakes, whereas if the ventilator body happens to be clearing with reference to the direction of the wind, those two intakes which are then on the windward side will be more effi- 55 cient than in the case of the round body venti- lator, and this for obvious reasons. In the modification shown in Figs. 4 and 5, the aspirating effect of the inflowing currents of air is extremely efficient upon the central 60 eduction passage, since this passage lies di- rectly underneath the angle where the air takes its turn and where the exhausting ef- fect is therefore most pronounced.

It is to be understood that the forms 65 shown are preferred but by no means the

only forms in which the invention may be efficiently embodied. I do not therefore limit myself to these details of construction, except in so far as they are made specific elements of the claims.

70

I claim as my invention:

1. In a ventilator, the combination of a trunk member, a head on said trunk member of greater mean cross-sectional area than said trunk, bottom and side walls extending 75 from the base of said head member and all terminating in the plane of the outer edge of said head member, said bottom and side walls forming air passageways from the sides of said head to the plane of its outer edge, the space between said walls being in communication with said trunk member.

2. In a ventilator, the combination of a trunk member, a head on said trunk member of greater mean cross-sectional area than 80 said trunk, bottom and side walls extending from the base of said head member and all terminating in the plane of the outer edge of said head member, said bottom and side walls forming air passageways from the sides of said head to the plane of its outer edge, the space between said walls being in communication with said trunk member, and a baffle member arranged opposite to but spaced away from the ends of said head 85 member and bottom and side passageway walls.

3. In a ventilator, the combination of a trunk member, a head on said trunk member of greater mean cross-sectional area than 90 said trunk, bottom and side walls extending from the base of said head member and all terminating in the plane of the outer edge of said head member, said bottom and side walls forming air passageways from the sides of said head to the plane of its outer edge, the space between said bottom and side walls communicating partly with the interior of said trunk member and partly with 95 atmosphere at their lower ends.

4. In a ventilator, the combination of a trunk member, a head on said trunk member of greater mean cross-sectional area than 100 said trunk, bottom and side walls extending from the base of said head member and all terminating in the plane of the outer edge of said head member, said bottom and side walls forming air passageways from the sides of said head to the plane of its outer edge, the space between said bottom and side walls communicating partly with the interior of said trunk member and partly with 105 atmosphere at their lower ends, and a baffle plate spaced a short distance away from the outlets of said passageways.

5. In a ventilator, the combination of a trunk member, a head on said trunk member of greater mean cross-sectional area than 110 said trunk, bottom and side walls extending from the base of said head member and all 115

125

130

terminating in the plane of the outer edge of said head member, said bottom and side walls forming air passageways from the sides of said head to the plane of its outer edge, the space between said walls being in communication with said trunk member, and a baffle member arranged opposite to but spaced away from the ends of said head

member and bottom and side passageway walls said baffle member having perforations 10 in register with the passageway outlets.
